LOCK

Harry A. Barrett, Philadelphia, Pa.

Application February 3, 1941, Serial No. 377,255

8 Claims. (Cl. 70—21)

This application for Letters Patent is a continuation in part of application for Letters Patent filed by me on February 6, 1939, Serial No. 254,974 for patent on Locks, which application is issuing as United States Patent No. 2,230,227 on February 4, 1941.

My invention relates to locks having permutation or combination or master-key release means.

One object of my invention is to provide a lock of the combination or permutation type, having means operable to assure positive disarrangement of the lock tumblers whenever the lockable member is released, so as to require a complete re-setting of the combination after each release.

Another object of my invention is to provide a lock of the combination or permutation type, so constructed as to permit return of a released lockable member to locking position regardless of the position of the tumblers.

A further object of my invention is to provide a combined master-key lock comprising combination or permutation means or both, which is springless, pick-proof, rugged and yet constructed of a minimum number of parts, as well as facile and inexpensive to manufacture.

Another object of my invention is to provide a combination master-key and permutation or combination lock which is incapable of being opened by an unauthorized person in possession of the master-key.

A further object of my invention is to provide a padlock having a sliding shackle and means operable to prevent inadvertent locking of a portion of the shackle while another portion is free.

With the above and other objects in view, my invention consists of a lock housing having movably mounted therethrough a locking member; a plurality of tumbler disks rotatably mounted in said housing, and containing registerable indentations on their peripheries, means in pivotal connection with said locking member operable to engage said peripheries when in locked condition and to move into said indentations when in release condition, and means positively to move said tumbler disks into locking position when said locking member is moved into release position.

My invention also consists of a lock comprising permutation tumblers adapted to be brought alternately into release and locking condition; a bolt; a dog pivotally secured to said bolt and rockable into release condition when said per-

mutation tumblers are in release condition; a dog-catch adapted to engage said dog and limit movement of said bolt when said tumblers are in locking condition and positive means to bring said dog-catch into locking engagement with said dog.

My invention further consists of a lock comprising combination or permutation tumbler means adapted alternately to be placed into release, and into locking condition; a bolt; a dog pivotally connected with said bolt alternately rockable and unrockable within definite arcs according to the respective release and locking conditions of said tumblers; a lever disposed within the path of said bolt and adapted to be rocked thereby when said bolt is brought into locking position; a dog-catch pivoted on said lever and having disposed at opposing sides of its pivot a bearing edge and a dog-detaining finger respectively; an eccentric adapted to bear against said lever when in one position operably to urge said dog-catch into engagement with said dog, and to release said lever when in another position operably to release said dog from engagement with said dog-catch; a key; means operable to permit said key to move said eccentric from one position thereof to the other; and means selectively to permit utilization of said key with said eccentric.

30 My invention also consists of a combination of a permutation lock and a key, comprising means for permitting said key to engage said permutation means operably to move said permutation means into release or locking condition according to a permutation series other than that required for operating the permutation means alone.

My invention further consists of a permutation lock comprising means operable to limit to one direction the movement of at least a portion of said permutation means operably to prevent the release of said lock on a "reverse combination" of said permutation means.

40 My invention also consists of a lock having a sliding and rotatable shackle and means for preventing the re-insertion of said shackle while it is rotated out of locking condition.

For the purpose of illustrating my invention, I have shown in the accompanying drawings forms thereof which are at present preferred by me, since the same have been found in practice to give satisfactory and reliable results, although it is to be understood that the various instrumentalities of which my invention consists can be variously arranged and organized and that my 50 invention is not limited to the precise arrange-

ments and organizations of the instrumentalities as herein shown and described.

Referring now to the drawings in which like references indicate like parts:

Figure 1 represents a front elevational view, partly broken away, of a lock embodying my invention and adapted for use in locker doors of the latch bar type.

Figure 2 represents a sectional view taken along the line 2-2 of Figure 1.

Figure 3 represents a vertical sectional view of the lock embodying my invention, taken along the line of 3-3 of Figure 2.

Figure 4 represents a sectional view of the lock embodying my invention taken generally along the line of 4-4 of Figure 3.

Figure 5 represents a vertical sectional view of a portion of the lock embodying my invention, when in locking condition, taken along the lines 5-5 of Figure 2.

Figure 6 represents the locking mechanism illustrated in Figure 5 when in release condition.

Figure 7 represents a sectional view of the key engaging portion of the lock embodying my invention and is taken generally along the line 7-7 of Figure 5.

Figure 8 represents a fragmentary view of the key (with the bow broken away) adapted to be used with the key engaging means illustrated in Figures 4-5-6-7.

Figure 9 represents a sectional fragmentary view of the key and key engaging means taken generally along the line 9-9 of Figure 7 and indicating the position of the key just before it is completely inserted into operating position.

Figure 10 represents the key and key engaging means as illustrated in Figure 9 when said key is completely inserted into operating position.

Figure 11 represents the permutation tumbler disks of the lock embodying my invention in proper alignment for releasing the bolt by means of the permutation disks. In this view the disks have been taken out and laid side by side for clarity of illustration.

Figure 12 represents the permutation disks of the lock embodying my invention in proper alignment for the use therewith of a key for the purpose of permitting the said key to bring said lock into release condition. In this view likewise the disks have been taken out and laid side by side for clarity of illustration.

Figure 13 represents an elevational view of a spacer washer embodied in the permutation tumbler mechanism of the lock embodying my invention.

Figure 14 represents a permutation tumbler of modified construction of a lock embodying my invention.

Figure 15 represents a fragmentary view of a lock embodying my invention as adapted for use as a padlock.

Figure 16 represents a sectional view of the shackle of the padlock illustrated in Figure 15, taken generally along the line 16-16 of Figure 15.

Figure 17 represents the tumblers of a permutation means of modified construction of a lock embodying my invention, in position for a release condition, and laid side by side for clarity of illustration.

Figure 18 represents a perspective view of the top, or drive, tumbler of a permutation means illustrated in Figure 17.

Figure 19 represents the key adapted to be used in conjunction with the permutation means illustrated in Figures 17 and 18.

Figure 20 represents an elevational view of the bearing and ward adapted to be used in conjunction with the key illustrated in Figure 19.

Figure 21 represents an elevational view of the cover-plate for use with the tumblers illustrated in Figures 11 and 12.

Figure 22 represents a front elevational view of the lock mechanism of modified construction embodying my invention showing the relation of the dial, key and key-way.

Figure 23 represents a vertical sectional view of a lock of another modified construction embodying my invention, as applied to a padlock.

According to my invention I provide a lock 30 having a dial 31 secured by means of a bezel or another suitable means 32 to a door 33 of a locker or other compartment 34 and having a bolt 35 vertically slidably mounted in a lock housing 36 and in engagement with a locking bar 37 to which is secured a suitable handle 38 operably to enable the locking or unlocking of the door 33 to a suitable jamb 39 in the compartment 34, all as substantially described in my co-pending patent application issuing as Patent No. 2,230,227. The lock housing 36 comprises a bottom or bed-plate 40 side-walls 41 and 42 and cover-plate 43. Secured to the cover-plate by any suitable means such as the lugs 44 a hollow, tubular disk-housing 45 projects towards the bed-plate and comprises a generally cylindrical wall 46 extending through an arc greater than 180° but short of 360° thereby to define an opening 47 facing the side-wall 42 through an aperture of which the bolt 35 is slidably disposed. The cylindrical wall 46 is preferably longitudinally outwardly beaded on opposed sides thereof between the axis and the opening 47 of said tube, as at 48, operably to define inner grooves 49 which are adapted to receive and retain nodes 50 outwardly projecting from suitable spacer washers 51. The bottom of the tube 45 is inwardly bent to form a base 52 adapted to receive and retain the bottom tumbler 53 of a series of permutation disk tumblers 53, 54 and 55 respectively.

The dial 31 has projecting from the rearward face thereof a drive pin adapted to revolve about a smaller circle with the rotation of the dial, said drive pin 56 being of sufficient length to project through the door 33, cover-plate 43 and into the path of rotation of the top tumbler disk 55. The cover-plate 43 and the tumbler disk 55 are centrally apertured as at 56 and 57 respectively to a diameter preferably but slightly greater than the path of revolution of the drive pin 56. A radial lug 58, preferably co-planar with the disk 55, projects into the aperture 57 into the path of revolution of the drive pin 56 and is adapted to be engaged and driven thereby. A lug 59 projects downwardly from the lower face of the disk 55 operably to engage an upwardly projecting lug 60 on the face of the intermediate tumbler disk 54 according to a well-known permutation disk principle. In like manner the downwardly projecting lug 61 on the disk 54 engages an upwardly projecting lug 62 on the disk 53. Registerable notches or other indentations 63 are formed in the outer peripheries of the tumbler disks 53, 54 and 55. Radially disposed grooves 64, 65 and 66 are formed along the inner peripheries in the tumbler disks 55, 54 and 53 respectively, in varying positions with respect to the notches 63 thereof and a corresponding radially disposed groove 67 is formed on the cover-plate 43. On the lower face of the bottom tumbler 53 I provide preferably a plurality of downwardly pro-

jecting lugs 67 disposed preferably co-radially and in substantial proximity to the outer periphery of the disk 53.

An outwardly projecting ear 68 is formed on the lower edge of the tube 45 and has pivoted to the lower face thereof a detent 69 comprising similarly projecting catches 70 and 71 adapted alternately to intercept the path of revolution of said downwardly projecting lugs 67 in a manner to prevent complete revolution of any one of said lugs in one direction while permitting the complete revolution of all the said lugs in another direction said complete revolution, however, causing the detent 69 to rock a plurality of times and effectuating a series of deceiving clicks when it is attempted to pick the lock. To increase said clicks and also to provide a limiting stop to the rotation of said detent 69 I provide an arm 72 adapted to bear against the side-wall 41 of the housing when said detent is at the preferred limit of one of its rocking positions. It will be noted further that by means of detent 69 it is impossible for the bottom tumbler 53 to be rotated in more than one direction and thus, it is impossible for the lock to be picked by means of discovering the reversely turned combination whereby the notches 63 may be brought into registry. Thus, the possibility of picking the lock is thereby reduced by one-half.

The bolt 35 comprises a sliding base 73, disposed within the housing 36 in juxtaposition to the side-wall 42, and the outwardly projecting latch member 74, the latter being adapted to slide within a suitable slotted aperture 75 within the side-wall 42. The sliding base 73 is longitudinally slotted as at 76 and is mounted on guiding studs 77 operably to be retained in position against the side-wall 42.

A dog 78 is preferably pivoted between the ends thereof as at 79 to the slideable base 73. A fence 80 projects upwardly from the dog 78 and is adapted to be rocked into the registered notches 63 of the tumblers 53, 54 and 55 when said notches are in juxtaposition thereto. A preferably curved arm 81 projects substantially towards the longitudinal axis of the housing 36 and has a plurality of functions as hereinafter described. The lower end of the dog 78 is formed into a hook 82 likewise projecting substantially toward the longitudinal axis of the housing 36.

A lever 83 is pivoted at the lower end thereof as at 84 to the bed-plate 40. A dog-catch 85 is pivoted on the lever 83 as at 86 preferably substantially below the lower edge of the arm 81 and above the hook 82 when the bolt 35 is in its lowermost position. A cam 87 is disposed on the upper side edge of the dog-catch 85 and is adapted to be engaged by the lower edge of the arm 81 of the dog 78 operably to rock dog-catch 85 in a counter-clockwise direction and to bring the step 88, comprising the lower edge of the dog-catch 85, into locking engagement with the hook 82 of the dog 78, when the bolt 35 is moved into its lowermost position. When the fence 80 is rocked into the registered notches 63 of the tumbler disks, however, the dog 78 is rotated about its pivot 79 operably to swing the hooked end 82 thereof sidewardly away from the step 88 and out of locking engagement therewith thereby to free the dog and the bolt on which it is pivoted operably to permit upward sliding thereof.

As the dog 78 moves upwardly the heel 89 of the hooked end 82 is engaged by the upwardly inclined cam 90 projecting inwardly from the

side-wall 42, and is rocked in a clockwise direction thereby to draw the fence 80 out of engagement with the tumbler notches 63. Further upward movement of the bolt 35 causes the upper edge 91 of the arm 81 to engage one of the downwardly projecting lugs 67 on the bottom tumbler disk 53 and to carry it upwardly with the dog 78, operably positively to disarrange the tumbler disks 53, 54 and 55. Thus, the tumbler notches 63 are not only brought out of release position with respect to the fence 80, but they are also disarranged so that there is no possibility of the fence passing therewithout the proper permutation series being again set.

Upon the lowering of the bolt from release position toward locking position, the fence 80 engages the outer peripheries of the tumbler disks 53, 54 and 55 and is cammed in a clockwise direction operably to rock the hook 82 toward engagement with the step 88 of the dog-catch 85, thereby causing said dog-catch likewise to rotate in a clockwise direction to permit the hook 82 to pass the step 88. Further downward motion of the dog 78, carried by the bolt 35 causes the arm 81 to bear against the cam 87 of the dog-catch and to rock said dog-catch in a counter-clockwise direction operably to cause the step 88 to engage with hook 82 and to lock it, as hereinbefore described. Thus, the bolt is locked.

An eccentric 92 is pivotally mounted on the bed-plate 40 concentric with the tumbler disks 53, 54 and 55. A step bearing 93 is formed within the pivot 94 on which the eccentric 92 is mounted and is adapted to receive the pin 95 of a key, which may be a master-key, 96. A notch 97 is formed on the eccentric 92 and is adapted to receive a crank pin 98 projecting from the said key 96.

The eccentric 92 bears downwardly upon a cam 99 formed on the upper side edge of the lever 83 and is adapted, when in its downward position, to cam said lever 83 into juxtaposition to the slideable base 73 of the bolt 35; and when in its raised position, to permit rocking of said lever 83 in a counter-clockwise direction away from juxtaposition to said slideable bolt 35. Thus, when the eccentric 92 is in its lower position, the dog-catch is in operating position with respect to the dog 78; and when the eccentric 92 is in its raised position, the dog-catch 85 carried by the lever is swung out of operating position with respect to the dog 78, as more clearly illustrated in Figure 6.

Suitable wards 100 are fixedly secured to the bed-plate 40 and are adapted to co-operate with inter-meshing wards 101 disposed on the key 96. A bell-crank 102 is pivoted to the rear face of the ward 100 and comprises a finger 103 adapted to project downwardly through a suitable aperture or against a suitable bearing edge 104 in the eccentric 92 when said eccentric is in its downward position, and to project also through a suitable aperture 105 in a portion of the bed-plate, operably to lock said eccentric against inadvertent rotation when the key is not in position for release thereof. A finger 106 extends from the opposing end of the bell-crank 102 into the path of insertion of the key 96 operably to be rocked thereby in a manner to cause withdrawal of the finger 103 from retaining engagement of the eccentric 92. Another finger 107 projects from the bell-crank above and to one side of the finger 106 operably to permit the key 96 to be passed into engagement with the lower finger 106, and to be rocked thereby into

engagement with the notch 108 of the key 96. Upward movement of the key, as in its withdrawal, causes the ward 109 forming one side of the notch 108 to engage the upper finger 107 and to rock the bell-crank 102 in a counter-clockwise direction into locking engagement with the eccentric 92.

In operation, the key 96 is inserted in the following manner: the dial 31 is rotated according to its pre-determined series which, in the case of a master-key, would be the same in all of the locks intended to be opened by the proper possessor of the said master-key; said pre-determined series being such as would bring the aperture notches 64, 65 and 66 of the tumbler disks into registry as indicated more clearly in Figure 12, and into registry with the notch 166 of the cover-plate 43. By this means, not only may no key be inserted until the proper master combination has been set, but because of the groove 166 in the fixed cover-plate, being a part of the registering combination, no unauthorized key may be inserted therethrough and turned therein to draw the other registering notches ad seriatum into the proper combination. After the proper combination is set, the key may then be passed through the notches and the apertures until it comes into operable registry with the wards 100. The crank pin 98 of the key 96 is thus brought into engagement with the eccentric 92 and rotation of the key causes the eccentric to rotate operably to permit the lever 83 and its dog-catch 85 to rock out of locking engagement with the dog 78, thus to permit said dog and its bolt to be slid upwardly into release position. To aid in this, I may also provide a trip-stud 168 to rock the dog-catch step away from the dog-hook. Reverse rotation of the key 96 causes the eccentric to cam against the lever 83 thereby to bring the dog-catch 85 into operably locking position with respect to the dog 78. If desired, a finger 164 may be disposed on the lever 83, in the downward path of the bolt 35 operable to permit the slideable base 73 thereof to bear there-against and to rock the lever 83 back into operating position.

In Figures 17 to 20, inclusive, and Figure 22 is illustrated a modified construction embodying my invention whereby the key operated permutation means employs a slightly different principle. Thus, I provide a key 112 having suitable wards 113 adapted to mesh with wards 114 upwardly projecting from a step bearing 115 mounted on the bed-plate 40, said step bearing 115 being adapted to receive the pin 116 of the key 112. The stem 117 of the key 112 passes through a suitable key-way 118 upwardly projecting through the knob of the dial 119 and in registry with a key slot 120 formed in said dial. The lower end of the key-way 118 is fixedly secured to the top tumbler 121 of a series of permutation disks 121, 122 and 123. If desired, the key-way 118 may be slidably rotated with respect to the disk 121, but in such case a suitable key receiving notch 124 should be formed in the key-way-receiving aperture of the tumbler 121.

A key-receiving aperture 125 is formed in intermediate tumbler disk 122 and has an arcuate wall 126 spaced from the center thereof a distance sufficient to enable the key stem 117 to rotate therethrough without interference, and also comprises a wall 128 adapted to be abutted by the key stem 117 in a manner to permit said key stem to bear there-against and to rotate the tumbler disk 122.

The bottom tumbler disk 123 likewise comprises

an aperture 129 of sufficient radius to permit the key stem 117 to pass therethrough without interference, and a lug 130 is formed on said tumbler 123 in a manner to project into said aperture 129 operably to intercept the path of rotation of said key stem 117 and to be moved thereby.

The tumbler disks also comprise suitable co-acting lugs 131 adapted to operate said tumblers according to the permutation system illustrated in Figure 11. By the use of the key 112, however, in conjunction with the tumbler disks 121, 122, and 123, the tumblers are operated by a permutation series variant from that of the lugs 131 operably to bring the notches 132 of the tumblers into registry. This variant permutation series is intended to be known only by the proper owner of the key. Thus, should the master-key 112 be lost or stolen, the un-authorized holder thereof would be utterly unable to unlock the locked mechanism of my invention without knowing also the proper combination with which it is intended to be used.

Where it is desired to use the key without the combination of a permutation series adapted for its use, the tumblers should be formed with a central aperture 133 of a diameter greater than the width of the stem 117, as more clearly illustrated in Figure 14.

In Figure 23 is illustrated a lock of modified construction embodying my invention, said lock being illustrated as applied to a padlock construction. According to this modified embodiment of my invention, I provide a lock casing 134 having side-walls 135 and 136 top and bottom walls 137 and 138 respectively and permutation disk means 139 mounted on the bed-plate 140, preferably substantially at the central axis of the casing 134. A slideable and rotatable shackle 141 having a toe 142 and an elongated heel 143 is slidably disposed within suitable apertures in the top wall 137 of the casing 134 and said heel 143 is suitably anchored within an upstanding wall 144 of a slideable bolt 145.

A dog 146 pivoted at its lower end, as at the pivot 147 to the lower portion of the bolt 145, is provided with a suitable fence 148 adapted to be rocked into registered notches 156 in the permutation means 139 when said notches are in juxtaposition to said fence 148.

The dog 146 has on its side edge a step 149 adapted to abut a rabbeted edge 150 of a suitable catch 151 pivoted at 152 to the bed-plate 140, the bolt 145 being slotted as at 153 to permit passage thereof about the dog-catch 151. The upper face of the rabbeted edge 150 is adapted to bear downwardly against the step 149 in a manner to lock the dog 146 and the bolt 145 against withdrawal. The slide bolt 145 has formed on the upper edge of the slot 153 an inclined bearing edge 154 adapted to bear against the upper edge 155 of the dog-catch 151 operably to rotate said catch in a clockwise direction in a manner to bring said rabbeted edge 150 into locking engagement with the step 149, when said bolt is moved downwardly into locking position. When the fence 148 is urged into the registered notches 156 as by an upward pull on the shackle 141 causing said step 149 to cam in a counter-clockwise direction against the upper inclined rabbeted edge 150 of the dog-catch, the dog is rocked out of engagement with the dog-catch 151 and is permitted to be moved upwardly operably to permit the shackle toe 142 to be withdrawn from the casing 134. Downward

movement of the shackle 141 carries with it the bolt 145 and causes the dog 146 to bear against the dog-catch 151 operably to rock the same out of limiting engagement with the dog 146 and to permit said dog to pass said catch 151 until the step 149 is beneath the rabbeted edge 150. Further downward motion of the bolt causes the catch to rock in a reverse direction as hereinbefore described operably to lock the dog 146.

A tumbler disarranging arm 157 projects from the bolt 145 in the path of the downwardly projecting lug on the bottom tumbler operably to intercept said lug and disarrange said tumblers when the shackle 141 is withdrawn.

In Figures 15 and 16 are illustrated means on the shackle of the lock embodying my invention operably to prevent the re-insertion of the said shackle when the toe 142 thereof is not in registry with the aperture adapted for its use in the top wall 137 of the casing 134. The heel 143 of the shackle 141 comprises a cylindrical anchor 158 rotatably disposed in the bearing 144, said cylinder projecting upwardly a suitable distance and being of a diameter smaller than that of the rest of the shackle and moreover being tangential to the arc of the cylinder of the upper portion of the heel 143 said upper cylinder 143 terminating in a perpendicular step 159 extending radially inwardly to the lower cylinder 160. If desired, a bearing 161 may be fixed to the bed-plate 140 and adapted to permit the sliding therethrough of the lower cylinder 160.

In operation, when the shackle 141 is withdrawn, as when the locked mechanism is in release condition the heel 143 of the shackle 141 is rotated about the axis 162 of the cylinder 160 thereby causing cylinder 143 to move in an eccentric and to cause the step 159 to bear against the upper edge 163 of the top wall 137 of the casing 134. Thus, the shackle is prevented from being re-inserted into the casing 134 while the step 159 bears against the top wall 137, and may only be re-entered into the casing when the toe 142 is in proper position for said re-entrance. In this manner the bolt is prevented from being locked while the shackle is still free.

I am aware that the invention may be embodied in other specific forms without departing from the spirit or essential attributes thereof, and I therefore desire the present embodiments to be considered in all respects as illustrative and not restrictive, reference being had to the appended claims rather than to the foregoing description to indicate the scope of the invention.

Having thus described my invention, what I claim as new and desire to secure by Letters Patent is:

1. A lock comprising a bolt, a dog in pivoted connection with said bolt, permutation means adapted to be moved alternately into locking condition and into release condition operably to restrain said dog and to permit rocking of said dog respectively; a lever; a dog-catch in pivoted connection with said lever and adapted when in one position to be engageable by the motion of said dog operably to lock the same, and when in another position to permit release of said dog; and means operable to rock said lever operably to move said dog-catch from one position thereof to the other.

2. A lock comprising a bolt, a dog in pivoted connection with said bolt, permutation means adapted to be moved alternately into locking condition and into release condition operably to restrain said dog and to permit rocking of said

dog respectively; a lever; a dog-catch in pivoted connection with said lever and adapted when in one position to be engageable by the motion of said dog operably to lock the same, and when in another position to permit release of said dog; and means adapted to be operably engaged by a key, operable to rock said lever operably to move said dog-catch from one position thereof to the other.

3. A lock comprising a bolt, a dog in pivoted connection with said bolt, permutation means adapted to be moved alternately into locking condition and into release condition operably to restrain said dog and to permit rocking of said dog respectively; a lever; a dog-catch in pivoted connection with said lever and adapted when in one position to be engageable by the motion of said dog operably to lock the same, and when in another position to permit release of said dog; and means adapted to be operably engaged by a key and co-operable with said permutation means, operable to rock said lever operably to move said dog-catch from one position thereof to the other.

4. A lock comprising a bolt, a dog in pivotal connection with said bolt, permutation means adapted to be moved alternately into locking condition and into release condition operably to restrain said dog and to permit rocking of said dog respectively; a lever; a dog-catch in pivotal connection with said lever and adapted when in one position to be engageable by the motion of said dog operably to lock the same, and when in another position to permit release of said dog; means operable to rock said lever operably to move said dog-catch from one position thereof to the other; and means deriving motion from said bolt operatively to change said permutation means from release condition to locking condition.

5. A lock comprising a bolt, a dog in pivotal connection with said bolt, permutation means adapted to be moved alternately into locking condition and into release condition operably to restrain said dog and to permit rocking of said dog respectively; a lever; a dog-catch in pivotal connection with said lever and adapted when in one position to be engageable by the motion of said dog operably to lock the same, and when in another position to permit release of said dog; means adapted to be operably engaged by a key, operable to rock said lever operably to move said dog-catch from one position thereof to the other; and means for preventing said lever from rocking when said key is not in use.

6. A lock comprising a bolt, a dog in pivotal connection with said bolt, permutation means adapted to be moved alternately into locking condition and into release condition operably to restrain said dog and to permit rocking of said dog respectively; means for limiting the direction of operation of at least one portion of said permutation means; a dog catch adapted when in one position to be engageable by the motion of said dog operably to lock the same, and when in another position to permit release of said dog.

7. A lock comprising a bolt, a dog in pivotal connection with said bolt, permutation means adapted to be moved alternately into locking condition and into release condition operably to restrain said dog and to permit rocking of said dog respectively; means for limiting the direction of operation of at least one portion of said permutation means; and operable to cause deceiving noises and motions when said lock is being

picked; a dog catch adapted when in one position to be engageable by the motion of said dog operably to lock the same, and when in another position to permit release of said dog.

8. A lock comprising a bolt, a dog pivoted to said bolt, permutation means adapted to be moved alternately into locking condition and into release condition operably to restrain said dog, and to permit rocking of said dog, respectively; a dog-

5 catch having means operable to permit motion of said dog during the movement of said bolt from release into locking position, and to restrain motion of said dog when said bolt and said permutation means are in locking position, and means on said bolt operable to move said dog-catch into said dog-restraining position.

HARRY A. BARRETT.
